METHOD OF MAKING CORN PLASTERS

George H. Perryman, Teaneck, N. J., assignor to
The Scholl Mfg. Co., Inc., a corporation of New
York

Application June 15, 1932, Serial No. 617,304

6 Claims. (Cl. 154—2)

This invention relates to a method of manufacturing corn plasters and other like articles. The object of the invention is to provide an improved method by which these articles may be rapidly manufactured in quantity; the method employed resulting in an improved product so manufactured that the sanitary characteristics desirable in an article of this kind are fully preserved.

10 Specifically, the invention contemplates the feeding of a strip or web of textile material coated on one of its faces with an adhesive or sticky substance and provided on its opposite face with a soft cushion material or pad; the 15 perforating of this strip or web, the perforations formed therein comprising the central openings appearing in the eventually-formed corn plasters; the uniting of a strip or web of a thin textile fabric backing with the first strip by adhesively uniting it with the soft back of the first strip, then dieing out the plasters from the composite strip, and adhesively attaching the plasters to a retaining strip of open-mesh fabric, and then severing the retaining strip into lengths, 20 each containing the requisite number of plasters. The process employed is a continuous one by which great speed in the manufacture of the plasters is attained.

25 In the accompanying drawing, Fig. 1 is a dia- 30 grammatic view illustrating the steps and mechanism employed in the manufacture of the plasters; Fig. 2 is a plan view of a part of the strip from which the main or body portion of the plasters is stamped showing the perforations formed in it; Fig. 3 is a view of the front face of one of the finished plasters; Fig. 4 is a view of the opposite face of the plaster; Fig. 5 is a sectional view on the line 5—5 of Fig. 3, looking in the direction 35 of the arrows; Fig. 6 is a plan view of a number of the plasters mounted on the foraminous back- 40 ing material; Fig. 7 is a sectional view through a part of the strip shown in Fig. 2; and Fig. 8 is a sectional view through the dies for stamping the perforations in the strip shown in Fig. 2.

45 The corn plaster manufactured in accordance with my improved process and shown in its finished state in Figs. 3 to 5, consists primarily of two main portions or layers; one portion con- 50 stitutes the body of the plaster and consists of a ring shaped pad or annulus 1 having an adhesive or sticky face 2 which is placed in contact with the toe and which adhesively holds the plaster in place. The other portion of the plas- 55 ter consists of a backing of a thin cotton fabric

3 which is adhesively attached to the back of the ring shaped portion 1 so that it covers the corn positioned within the central opening 15 of the ring 1 when the plaster is worn. These plasters may be made in any shape to suit different requirements, the conventional oval shape being herein shown for convenience. When sold, the plasters are mounted for protective purposes upon a strip or sheet of an open-mesh textile fabric 20 such as crinoline, on which they are held by the adhesive material 2. This backing 20 is impregnated with a suitable substance which permits the plaster to be easily stripped from it when the plaster is ready for applica- 5 10 15

10 In carrying out the process of the invention, I utilize a main strip or web 1a, from which the part 1 of the corn plaster is made. This strip is fed from a roll 11 by any suitable feeding means and passes under a roller 12 and between dies 13 and 14 which produce the regularly spaced openings or holes 15 in the strip, these openings or holes constituting those formed in the center of the body portion 1 of the finished plaster. The strip 1a is composed of a textile fabric having a soft pad-like back 17 and its opposite face, shown uppermost in Fig. 1, coated with the adhesive or sticky material 2. As strip or web 1a is fed between the dies 13 and 14 which form the holes 15, the disk material 21 punched out of these holes is carried away or otherwise disposed of in any suitable manner, as for instance, by being forced up through the hollow male die 13 by the action of a stud 18 located in the female die 14, as shown in Fig. 8. Any other means for removing this waste material 21 may be used.

20 25 30 35 40 45 50 55 When the perforated web 1a leaves the dies 13 and 14, it is moved between rollers 22 and 23 in company with a web 3a fed from a roll 35 and of the thin textile fabric which forms the backing 3 of the completed plaster. The web 3a has a sticky or adhesive face 24 which may be medicated if desired, and which, when brought in contact with the soft back 17 of the web 1a by the pressure of the rollers 22 and 23, causes the two strips 1a and 3a to be adhesively united. The composite strip, consisting of the two layers 1a and 3a is now fed between dies 25 and 26 which operate on the dotted lines in Fig. 2 to punch out the plasters. The male die 25 forces the plasters shown at 27 in Fig. 1 out of the strip, its upward movement bringing the plasters against the face of a strip 20 of open-mesh fabric or other foraminous material, fed from a roll 28, 60 65 70 75 80 85 90 95

passing under a roller 29 and moving beneath a plate 30 against which it is forced by the pressure of the male die 25 when said die presses the plasters against its under face. The adhesive face 2 of the plasters punched out from the composite strip, when brought into contact with the open-mesh fabric, attaches the plasters on the strip and the plasters are carried thereby.

10 As the strip 20 moves away from the dies 26 and 27, bearing the plasters on its under face, the plasters so carried are brought across the face of a heated plate 31, which softens the adhesive located between the face 24 of the fabric 15 backing 3 and the back 17 of the strip 10 so that a very secure adhesion between the fabric backing 3 and the body portion 1 of each of the plasters results. The plate 31 is maintained at such a temperature as not to materially affect 20 the adhesive face 2 of the plasters so that no difficulty is had by the user of the plasters in stripping them bodily from their backing strip 20 when he desires to use them.

The strip 20 carrying the plasters 27 is next 25 carried between knife members 32, which sever the strip into lengths, each length carrying the required number of plasters, these lengths being then ready for packing.

While the heating plate 31 is shown as positioned 30 between the dies 25 and 26 and the cutters 32 and 33, it can also be located between the rollers 22, 23 and the dies 25 and 26, where it will function to securely unite the adhesive on the face 24 of the thin fabric backing with the 35 soft back 17 of the strip 1a.

The webs or strips from which the plasters are formed may be of any suitable widths, the punching dies employed to operate on these webs being accordingly increased in number or mounted in 40 gangs, when necessary, so that quantity production will be had.

These and various other changes may be made 45 without departing from the spirit of this invention.

45. What I claim is:

1. The process of making corn plasters and the like, consisting in feeding a composite web of fabric, one of the layers of the web being provided with spaced perforations and having an 50 exposed sticky surface, in stamping corn plasters from the composite web with a die and forcing them out of the web by the die and pressing them against a web of open-mesh textile fabric by the die to adhesively attach them thereto, in moving 55 the plasters over a heated surface while carried on the web of open-mesh textile fabric and in cutting the fabric into sections.

2. The process of making corn plasters and the like consisting in feeding a web composed of a 60 pad-like material provided with a stick surface, perforating the web and forcing waste material out of the perforations simultaneously with the

perforating operation, adhesively uniting a textile fabric backing to the back of the perforated web to thus form a composite web, punching out plasters from the composite web and forcing said plasters away from the web by the punching operation, feeding a web of foraminous fabric adjacent to the composite web so that the punched-out plasters are directed against said foraminous fabric when said plasters are punched out of the composite web, carrying the backs of the plasters against a heated member while said plasters are attached to the foraminous fabric, and severing the foraminous fabric into lengths.

3. The process of making corn plasters consisting in feeding several fabric webs, at least 15 one of which is provided with a sticky face, perforating the sticky-faced web and adhesively uniting it with at least a second web, punching corn plasters from the webs thus united and simultaneously forcing the corn plasters out of the 20 united webs and into contact with a fabric backing to adhesively attach them thereto, and bringing the fabric backing and plasters adhering thereto over a heated element to intimately bond the plasters to the backing.

4. In the process of making corn plasters, the steps of stamping out plasters from a fabric web and forcing the plasters out of and away from the web by the stamping operation and bringing them into contact with a fabric backing to stick 30 them thereon, and in bringing the plasters and fabric backing into contact with a heated element to bond the plasters to the backing.

5. The process of making corn plasters consisting in feeding several fabric webs, at least one 35 of which is provided with a sticky face, perforating the sticky faced web and adhesively uniting it with at least a second web, punching corn plasters from the webs thus united and simultaneously forcing the corn plasters out of the 40 united webs and into contact with the fabric backing to adhesively attach them thereto, and bringing the fabric backing and plasters adhering thereto across a heated element with the fabric backing remotely disposed from the element 45 to thereby bond the plaster webs.

6. The process of making corn plasters consisting in feeding several fabric webs, at least one of which is provided with a sticky face, perforating the sticky faced web and adhesively uniting it with at least a second web, punching corn plasters from the webs thus united and simultaneously forcing the corn plasters out of the 50 united webs and into contact with the fabric backing to adhesively attach them thereto, and bringing the fabric backing and plasters adhering thereto across a heated element, the element being located to apply a more intensive heat to the 55 contacting faces of the plaster webs than the contacting faces of the fabric backing and the touching plaster web.

GEORGE H. PERRYMAN.
